Inventor Ebenezer Curfice

United States Patent Office.

EBENEZER CURTICE, OF YONKERS, NEW YORK.

Letters Patent No. 61,927, dated February 12, 1867.

HYMN AND TUNE-BOOK.

The Schedule referred to in these Letters Patent and making part of the same.

TO ALL WHOM IT MAY CONCERN:

Be it known that I, EBENEZER CURTICE, of Yoakers, in the county of Westchester, in the State of New York, have made an invention to apply to Hymn and Tune-Books; and I do hereby declare that the following is a full and exact description thereof, reference being had to the accompanying drawings, and to the letters of reference marked thereon.

This invention consists in applying to books made with the leaves cut in two transversely, between the hymns and tunes, as shown by the diagrams, in which the lines marked *f* show where the leaves are cut in two, the tunes being printed on the parts marked *a*, and hymns on the parts marked *b*, the whole leaves *c* intervening different parts of the book for the purpose of separating the different metres. The leaves marked *c*, fig. 1, show some of the intervening whole leaves. Also in applying a holder to the book for the purpose of keeping the cut leaves open and in place while the book is in use. The holder, in the accompanying drawing, is the piece of binding or braid, *d*, with the tin slide *e* on it, and is attached at the top of the book. It can be made of any other suitable material. When in use, it is brought over the open book and the slide so adjusted as to bear on all four of the open leaves. It is held in place by the thumb of the hand holding the book, as shown in fig. 2. By this invention all the hymns of the same metre may be sung to any tune of like metre in the book, the singer having both words and music open before him. All the long-metre hymns can be sung to the tune Old Hundred by simply turning over the bottom leaves, having the top leaves open to the tune Old Hundred.

What I claim as my invention, and for which I wish to secure Letters Patent, is—

1. In singing-books, having their leaves cut as herein described, the use of whole leaves intervening the cut leaves, for the purpose mentioned herein.
2. The application of a holder, in the manner and for the purpose herein specified.

EBENEZER CURTICE.
